UNITED STATES PATENT OFFICE.

CARL J. THIM, OF LOGAN, UTAH.

CLASP.

Application filed November 7, 1927. Serial No. 231,595.

This invention relates to clasps or buckles, and more particularly to a clasp or buckle especially designed for use in connection with supporting belts, garters or the like, and aims to provide a novel form of clasp or buckle so constructed that no portion of the metal of which the clasp or buckle is formed, will touch the body of the user.

An important object of the invention is to provide a clasp or buckle of this type including a pair of prongs so arranged that the articles supported thereby will be held or supported in a spread condition so that the article will not roll to the discomfort of the user.

A still further object of the invention is the provision of a clasp or buckle which may be stamped from sheet metal by a single stamping operation, thereby providing a device of this character which may be made at a comparatively small cost so that it may be cheaply sold to the public.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is an elevational view showing a buckle constructed in accordance with the invention and secured to a supporting strap.

Figure 2 is a vertical sectional view through the buckle and supporting strap.

Figure 3 is a perspective view of the clasp or buckle.

Referring to the drawing in detail, the device includes a main or body portion 5 which is formed of a length of substantially wide sheet metal, the same being provided with lateral extensions 6 bent upwardly and inwardly as at 7 defining keepers for the prongs 8 that are formed by bending a length of metal intermediate its ends as clearly shown by Figure 1.

The body portion is stamped in such a way that bearings 9 are provided in which the prongs are pivotally mounted, the intermediate portion of the prongs being curved as at 10 to prevent lateral movement of the prongs with respect to the base 5, and to also place the prongs 8 under tension and cause them to be normally urged into close engagement with the keepers 7.

The prongs 8 are offset at points adjacent to the outer ends of the bearings 9, so that the prongs lie in spaced relation with the base 5 adding resiliency to the prongs to cause them to closely engage within the keepers 7.

Thus it will be seen that due to this construction all possibility of the prongs becoming accidentally displaced, will be prevented.

At one end of the body portion is an elongated opening 11 to which the extension 12 may be secured, while at the opposite end of the body portion is an extension 13 formed with an eye so that threads may be passed therethrough to secure the clasp or buckle to its supporting strap.

The supporting strap is indicated by the numeral 14 and may hang down from a suitable supporting belt or a garter where it may be secured to the article to be supported.

I claim:

A buckle including a body portion formed of sheet metal and having lateral extensions formed adjacent to one end thereof, said extensions being curved inwardly defining keepers, bearings adjacent to the opposite end of the body portion, prongs including a central portion fitted in the bearings and having outwardly extended offset portions adjacent to the outer ends of the bearings to add resiliency to the prongs, and said central portion being curved at points between the bearings to engage the body portion to restrict movement of the prongs.

In testimony that I claim the foregoing as my own, I have hereto affixed my signature.

CARL J. THIM.
